UNITED STATES PATENT OFFICE.

TOMAS E. LAROY, OF EHRMANDALE, INDIANA, ASSIGNOR OF TWO-THIRDS TO JOHN SCOTT AND THOMAS SCOTT, OF VIGO COUNTY, INDIANA.

RAIL-JOINT.

SPECIFICATION forming part of Letters Patent No. 780,893, dated January 24, 1905.

Application filed October 29, 1904. Serial No. 230,528.

To all whom it may concern:

Be it known that I, TOMAS E. LAROY, a citizen of the United States, residing at Ehrmandale, in the county of Vigo and State of Indiana, have invented a new and Improved Rail-Joint, of which the following is a specification.

My invention relates to joints for railway-rails.

The object had in view is to provide means in the make-up of such joints whereby improved fastening of the rails may be effected by means which shall also brace the rails against spreading action.

The invention consists of the special construction, arrangement, and combination of parts shown in the accompanying drawings and which will hereinafter be fully described, the novel features being pointed out in the subjoined claims.

In the drawings, Figure 1 is a perspective view in illustration of my invention. Fig. 2 is a transverse sectional view taken on line 2 2 of Fig. 1, and Fig. 3 is a detail plan view of the under side of two rails arranged end to end and connected by my improved key.

In the practice of my invention I provide hook-shaped or turned-up flanges A on opposite sides of the rail-webs, with the same extending from about the point A' thereon to the abutting ends of the rails, as will be understood upon reference to Fig. 1.

The flanges A may be integral with the rails or constructed of plates A², having necessary bent side edges and with the plate arranged in a suitable slot or recess A³ in the rail-webs at the adjacent ends of the rails.

B denotes a chair into which the end B' of one rail is slid to about half-way thereof. In the remaining portion of the chair the end B² of the next adjacent rail is likewise arranged, as shown in Fig. 1.

The spaced ends B³ of the chair B are bent or fashioned along their upper edges adapted to receive the flanges A and turned inwardly and downward, thereby forming hooks B⁴, adapted for locking engagement with the flanges A. (See Fig. 2.)

C denotes brace devices located on oppo-

site sides of the rail-joint. The braces are intended to prevent spreading of the rails and provide the joint with additional rigidity. They also afford means adapting ready spiking of the rails to the cross-ties.

It will be noticed that the braces C are constructed with lateral extensions C', having therein suitable openings C², through which and into the cross-tie the prongs D of a three-pointed spike D' may be driven. The middle prong D of the spike is intended to be the longer; but obviously the spiking may be made with three separate ordinary spikes.

The outer edges of the extensions C' may be provided with arms C³, having turned-down points C⁴ adapted to be driven into the cross-tie.

The inner edge of the braces C is fashioned into substantially an upright portion C⁵ thereof and which portion may or may not be cut away between its ends, leaving an opening, as at C⁶. (See Fig. 1.)

Upon reference to Fig. 2 of my drawings it will be noticed that the edge of the upright portion C⁵ of the brace C is bent into an inwardly-disposed hook C⁷, adapted for locking engagement with the flange A and the interposed hooked edge B⁴ of the rail-chair B.

The locking feature or upper edge C⁷ of the brace C is secured against vertical displacement when the brace is spiked to the cross-tie by means thereupon of an upwardly-disposed flange C⁸.

The inner side of the flange C⁸ and the downwardly-turned edge C⁷ are disposed and adapted to bear against the rail-web, and said flange and edge are secured against vertical displacement by confinement thereof between the under side of the rail-head and the flange A, substantially as shown in Fig. 2.

It is apparent from the above description that the rail-chair, as also the braces, are securely locked to the rail against vertical displacement and that they are arranged in joint-forming position by endwise sliding adjustment.

In the base or under side of the rails I form wedge-shaped recesses 1, adapted to receive

the ends of a double-wedge-shaped key 2. The key is constructed with rigid end portions 3 and reduced or yielding sides 4.

The openings 5 of the recesses 1 are made 5 sufficiently wide to permit lateral movement of the key sides 4 during expansion and contracting action of the rails.

My improved rail-joint has advantage over 10 all similar joints known to me in the means employed for locking the chair and braces to the rail and also in the special construction, arrangement, and combination of parts forming the joint.

Having thus described my invention, what 15 I claim as new, and desire to secure by Letters Patent, is—

1. In a rail-joint, means for supporting the adjacent rail ends, and locking means on the rail ends and the supporting means, adapted 20 for connection through endwise adjustment of the supporting means, substantially as described.

2. The combination in a rail-joint, of a chair 25 into which the rail ends have endwise insertion, locking - flanges on the rail ends, and hooked edges on the chair, adapted for endwise adjustment into locking engagement with said flanges on the rail-web, and also, whereby 30 vertical separating action of the rail and chair edges is prevented, substantially as described.

3. The combination in a rail-joint, of a chair 35 into which the rail ends have endwise insertion, locking-flanges on the rail-webs, locking

edges on the chair,adapted for endwise engagement with said flanges, and braces having locking inner ends, adapted upon endwise movement, for connection to the flanges on the rail-web and whereby, to prevent vertical separating movement of the braces, substantially as described.

4. The combination in a rail-joint, of means 40 for supporting the adjacent rail ends, locking-flanges on the web of the rails, and braces adapted to be secured to the cross-ties, having hooked inner ends adapted upon endwise adjustment, for locking engagement with said flanges on the rails, and at the same time obviating vertical disconnecting action, substantially as described.

5. In a rail-joint, means supporting and 45 securing the rails, and a yielding key connecting the abutting ends of the rails, substantially as described.

6. In a rail-joint, a connecting-key having rigid ends and yielding sides, substantially as 50 described.

7. The combination in a rail-joint, of means supporting and securing the rails, and a double-wedge-shaped key arranged in suitable recesses in the base of the rails, the key having 55 yielding sides, substantially as described.

TOMAS E. LAROY.
